UNITED STATES PATENT OFFICE.

JOHN F. WOLLENSAK, OF CHICAGO, ILLINOIS.

SPEAKING-TUBE WHISTLE.

SPECIFICATION forming part of Letters Patent No. 427,720, dated May 13, 1890.

Application filed December 30, 1889, Serial No. 335,414. (No model.)

To all whom it may concern:

Be it known that I, JOHN F. WOLLENSAK, a citizen of the United States, residing at Chicago, Illinois, have invented certain new and 5 useful improvements in Speaking-Tube Whistles, of which the following is a specification.

The object of my invention is to provide means to hold the piece containing the whistle in its proper central position, and prevent 10 its being moved to one side or the other and my invention consists in the features and 15 details of construction hereinafter described and claimed.

In the drawing, Figure 1 is a vertical section of a speaking-tube whistle, showing the whistle-piece turned back to open the tube, and Fig. 2 is a plan view of a section taken in the line 2 of Fig. 1, looking in the direction of the arrow and showing the whistle-piece 20 down in its central or normal position.

Heretofore the whistle-piece in speaking-tubes has been fastened to a rod extending through the tube and provided at the outer end with a small crank to enable a person to 25 turn the whistle-piece back to open the end of the tube. This crank-rod has been provided with a spring whose tendency is to hold the whistle-piece in that position which closes the end of the tube. This spring by itself 30 has not been able, however, to prevent lateral displacement of the whistle-piece and to hold it in a true central position, and it has therefore been liable to be moved toward one side or the other, as the crank-rod to which it is 35 fastened is pulled or pushed in the one direction or the other. This movement to one side makes an opening at the side of the whistle-piece, through which the air can escape and fail to operate the whistle. This defect has been a matter of annoyance and trouble in the practical operation of speaking-tube

provided with whistles. In my improvement I overcome this objection and positively secure the whistle-piece in its normal central position, so that it will always cause the 45 whistle to sound.

In making my improvement I take the ordinary shell or case A, whistle-piece B, rod C, and spring D, arranged in the usual way. I arrange a piece or connection E between the 50 crank-rod and whistle-piece, provided with shoulders e, and solder the same to the rod and the whistle-piece. The shoulders e extend out far enough on either side to come into contact with the shell or case in which 55 the whistle-piece is arranged. By thus contacting with the shell or case they prevent the rod from being moved or slid in the one direction or the other, and so operate to constantly hold it in its normal central position. 60 This positive holding of the whistle-piece always insures the proper operation of the whistle when the tube is blown into, and overcomes the defect of lateral displacement, which, in the absence of means to hold the 65 whistle-piece in its central position, often rendered the whistle inoperative and useless.

What I regard as new, and desire to secure by Letters Patent, is—

In a speaking-tube, the combination of a 70 shell or case, a whistle-piece arranged therein, a crank-rod for turning the whistle-piece, and a connection between the crank-rod and the whistle-piece, provided with shoulders abutting against the sides of the shell or case and 75 holding the whistle-piece in its true central position against lateral displacement, substantially as described.

JOHN F. WOLLENSAK.
